UNITED STATES PATENT OFFICE

2,526,816

DETACHABLE TELESCOPE SIGHT MOUNT
FOR FIREARMSRobert R. Hardgrove, Livingston, Mont., assignor
of one-half to Ernest T. Lake, Livingston, Mont.

Application June 13, 1949, Serial No. 98,810

1 Claim. (Cl. 33—50)

1

This invention relates to an improved mounting for detachably and accurately positioning a telescope sight on a firearm such as a rifle and has for its primary object to provide a sight mount which may be quickly and easily applied to rifles without requiring the use of special tools other than a tool for drilling and tapping holes or recesses in the receivers of certain firearms.

More particularly, it is an aim of the present invention to provide a telescope sight mount including adapters milled to fit receivers of different firearms and having a multi-sided upper surface providing a seat for the base portion of a standard mounting bracket, constituting a part of the sight mount and which will afford the maximum stability for the mounting bracket to maintain said bracket properly seated on the adapter when the telescope sight is detachably clamped to the firearm.

Still another object of the invention is to provide a mount wherein pressure of the recoil of the firearm is against a stationary retaining element of the mount rather than against a resiliently supported retaining element.

Various other objects and advantages of the invention will hereinafter become more fully apparent from the following description of the drawing, illustrating a presently preferred embodiment thereof, and wherein:

Figure 1 is a side elevational view, partly in vertical section, showing a portion of a rifle with a telescope sight detachably mounted thereon by the side mount;

Figure 2 is a top plan view of the receiver portion of the rifle showing the telescope sight removed therefrom;

Figures 3 and 4 are cross sectional views taken substantially along planes as indicated by the lines 3—3 and 4—4, respectively, of Figure 1, Figure 3 being on an enlarged scale, and

Figure 5 is a longitudinal sectional view taken substantially along a plane as indicated by the line 5—5 of Figure 2 and showing the sight applied.

Referring more specifically to the drawing, for the purpose of illustrating a preferred application and use of the detachable telescope sight mount, designated generally 6 and comprising the invention, the receiver portion, designated 7 of a conventional rifle and a conventional telescopic sight, designated generally 8, have been illustrated in the drawing to illustrate the application and use of the sight mount 6.

The sight mount 6 includes a front adapter, designated generally 9 and a rear adapter, desig-

nated generally 10. As best illustrated in Figure 3, the front adapter 9 is provided with a concave cross sectional bottom surface 11 which is adapted to fit flush on the upper surface of the receiver 7 forwardly of the ejector opening 12 of said receiver. Said under surface 11 may vary in shape to adapt it to fit flush against the upper surface of receivers of different shapes. The upper surface of the front adapter 9 includes a substantially flat longitudinally extending central portion 13 and upwardly converging side portions 14 which merge with the side edges of the central portion 13 to form a three sided top surface preferably corresponding to three sides 15 of an octagon. The inner or rear end of the adapter 9 is provided with a rearwardly opening notch 16 which tapers toward its forward or closed end and which preferably has a rounded upper surface, as clearly illustrated in Figure 3.

20 The adapter 9 is provided with longitudinally spaced openings 16 in the top surface thereof, as seen in Figure 5, to receive screws 17 which are countersunk therein and which detachably engage in threaded recesses 18 of the receiver 7 for detachably mounting the adapter 9 thereon.

The adapter 10 is provided with an under surface 19 which is concave in cross section to engage flush on another portion of the receiver 7 and is provided at one side thereof with a longitudinally extending depending lip 20 and at its opposite side with a longitudinally extending depending flange 21, which lip and flange engage opposite sides of the receiver 7. The flange 21 is provided with openings for receiving screw fastenings 22 which engage threaded recesses in a side of the receiver 7, one of which is indicated in dotted lines at 23 in Figure 4. The adapter 10 likewise is provided with a three sided upper surface including a substantially flat horizontally disposed intermediate top portion 24 and upwardly converging side surfaces 25 which likewise extend longitudinally of the adapter 10 and the upper edges of which merge with the side edges of the top surface 24.

45 It will be understood that the side portions and bottom surfaces of the adapters 9 and 10 may vary to accommodate them to receiver surfaces of different shapes and that the location of the fastening receiving opening may likewise be varied and, in many cases, may be located to receive fastenings for engagement with tapped recesses or openings already provided in the firearm receiver so that it will not be necessary to tap the openings 18 and 23 to receive the fastenings 17 and 22.

The telescope sight mounting 6 also includes a front mounting bracket, designated generally 26 and a rear mounting bracket, designated generally 27. The mounting brackets 26 and 27 are provided with corresponding bores 28 extending therethrough for detachably receiving the barrel of the telescope sight 8 and said brackets have split upper portions 29 which are connected by screws 30 which slidably engage in bore portions 31 thereof and threadedly engage other aligned bore portions 32 so that the screws 30 may be tightened for clamping the sight barrel in the bores 28 and with the depending portions of said brackets 26 and 27 in alignment, for a purpose which will hereinafter become apparent. The depending, leg portion 33 of the front mounting bracket 26 is provided with a three sided bottom surface 34 which is shaped to seat flush on the top surface portions 13 and 14 of the adapter 9, as clearly illustrated in Figure 3. Said leg 33 is provided with an integral rearwardly projecting hook shank 35 which terminates at its rear, free end in a depending, forwardly extending hook 36 having a downwardly and forwardly inclined upper surface which is adapted to seat in the rearwardly opening notch 15 when the bottom supporting bracket surface 34 is seated on the upper adapter surface 13, 14.

The mounting bracket 27 is likewise provided with a depending portion or leg 37 having a recessed three sided bottom surface or foot portion 38 which is shaped to seat flush on the upper surface 24, 25 of the rear adapter 10, as clearly illustrated in Figure 4. Said rear adapter 10 is provided at its forward end with a forwardly opening, rearwardly tapering notch 39 having a rounded upper surface, as seen in Figure 4.

A collar 40 is disposed on the barrel of the sight 8, between the mounting brackets 26 and 27 and adjacent said forward mounting bracket 26 and is held against forward movement toward the mounting bracket 26 by a stop 41, which is disposed on the barrel between the collar 40 and bracket 26. An elongated sleeve 42 has its forward end slidably engaging on the collar 40 and is provided with an integral annular flange 43 at its rear end for slidably engaging the barrel of the sight 8 and the inner surface of which forms a seat for one end of an expansion coil spring 44 which is disposed within the sleeve 42 and around the sight barrel and which has its opposite end seated against the rear end of the collar 40 for urging the sleeve 42 rearwardly or toward the mounting bracket 27. The sleeve 42 is provided with an integral hook 45 which projects laterally therefrom, adjacent its rear end and which is normally disposed in a depending position and which has a rearwardly extending bill 46 provided with a downwardly and rearwardly inclined upper surface shaped to seat snugly in the recess 39.

From the foregoing it will be readily apparent that the sight 8 when positioned as seen in Figure 1 may be readily demounted from the firearm receiver 1 by manually grasping the externally roughened surface 47 of the sleeve 42 for forcing said sleeve forwardly or toward the front mounting bracket 26 against the action of its spring 44 to disengage the hook 45 from the recess 39 so that the telescope sight 8 can then be swung upwardly on the bracket 26 as a pivot for disengaging the hook 36 from the recess 15 to thereby quickly and easily demount the sight from the receiver.

It will likewise be readily apparent that the 75 shaped to seat flush on the upper surface of one

sight can be quickly and easily mounted on the receiver by positioning the forward edge of the bottom surface 34 of the bracket 26 in engagement with the top surface of the adapter 9 and then rocking the rear end of the sight downwardly until a portion of the hook 36 engages the notch 15. By then exerting a forward pressure on the sleeve 42, said sleeve can be displaced forwardly of the sight 8 so that its hook 45 will clear the forward end of the adapter 10 to permit the bottom surface 38 of the mounting bracket 27 to be moved downwardly into engagement with the surface portions 24 and 25 of the adapter 10 after which pressure on the sleeve is released to permit the spring 44 to displace the sleeve and hook 45 rearwardly for engaging the hook in the notch 39 and to also fully seat the hook 36 in the notch 15. The pressure of the spring 44 will tend to displace the hooks into the notches and the upper inclined surfaces of said hooks by engagement with the inclined upper surfaces of the notches will cam the mounting brackets 26 and 27 downwardly and into flush seating engagement with the top surfaces of the adapters 9 and 10 so that the sight 8 will be correctly positioned above and in alignment with the firearm barrel and the engagement of the foot portions 34 and 38 of the mounting brackets 26 and 27, respectively, with the front and rear adapters 9 and 10, respectively, will prevent any lateral displacement of the sight 8, when in an applied position, to insure a proper mounting of the sight.

Furthermore, it will be noted that the spring 44 exerts a rearward force against the movable hook 45 so that the recoil of the firearm will be against the stationary hook 36 so as not to cause any vibration of the sight relatively to the firearm.

From the foregoing it will be readily apparent 40 that the sight mount 6 may be readily applied to firearm receivers, sometimes without even the necessity of drilling holes for the screw fastenings 17 and 22 and on other occasions merely by drilling and tapping such recesses or openings. 45 As the notches 15 and 39 are already formed in the adapters 9 and 10 no milling operation is required thereby making it a relatively simple operation for any gunsmith to apply the sight mount to a firearm.

As previously stated, the shape of the under sides of the adapters 9 and 10 may vary to accommodate them to receiver surfaces of different shapes and the location of the fastening receiving openings thereof may likewise be varied to 55 accommodate them to tapped recesses or bores where already provided.

Various other modifications and changes are contemplated and may obviously be resorted to, without departing from the spirit or scope of the 60 invention as hereinafter defined by the appended claim.

I claim as my invention:

A detachable telescope sight mount for firearms comprising a pair of adapters adapted to be detachably fastened to the upper surface of the receiver of a firearm in longitudinally spaced relationship, said adapters each having a multi-sided upper surface disposed longitudinally of the firearm, a pair of mounting brackets adapted to be detachably clamped to the barrel of a telescope sight in longitudinally spaced relationship and supported on the adapters, said mounting brackets having aligned depending legs each provided with a recessed, multi-sided bottom surface 70 shaped to seat flush on the upper surface of one

2,526,816

5

of the adapters, said adapters having notches opening outwardly of the adjacent ends thereof, a hook formed integral with one of said mounting brackets and detachably engaging the notch of one of the adapters, a hook reciprocally mounted on the barrel of the telescope sight and detachably engaging the notch of the other adapter, spring means yieldably biasing said last mentioned hook toward the last mentioned adapter notch, a sleeve adapted to be reciprocally disposed on the telescope sight barrel and forming an integral part of said last mentioned hook, said sleeve having an internally restricted end adapted to slidably engage the sight barrel to support one end of the sleeve thereon, and a collar adapted to be mounted on the sight barrel and on which the opposite end of said sleeve is slidably mounted

6

and supported, said spring means bearing with one end against an end of said collar and having its opposite end bearing against the internally restricted end of the sleeve and enclosed within said sleeve.

5 ROBERT R. HARDGROVE.
